UNITED STATES PATENT OFFICE

HARRY P. WICKERSHAM, OF HUNTINGTON PARK, CALIFORNIA

JAR

Application filed March 20, 1931. Serial No. 524,018.

This invention relates to a well tool, and relates more particularly to a jar for effecting a jarring action in a well. It is a general object of the present invention to provide a jarring tool for use in fishing operations, or the like, that is operable to provide a heavy, powerful jarring action for loosening objects caught in a well.

It is an object of this invention to provide a rotary jar that is adapted to be actuated by putting an upward pull or tensile strain on the operating string.

It is another object of the invention to provide a jarring tool that may be easily and quickly re-set for actuation without being withdrawn from the well bore. The tool provided by the present invention may be actuated a number of times in rapid succession to effect the jarring blows by simple reciprocation of the operating string while maintaining a torsional strain on the string.

It is another object of the invention to provide a jarring tool of the character mentioned that may be set to trip or actuate under various tensile strains to provide jarring actions of different intensities. In employing the tool, the power of the jarring action obtained may be governed or controlled by controlling the torsional strain applied to or maintained on the tool.

Another object of the invention is to provide a jar of the character mentioned in which an effective fluid-tight seal is formed between the sections of the tool around their fluid passages without the use of packing glands, or the like.

It is an important object of the present invention to provide a jarring tool in which there is no rotative movement between the parts which come into contact to provide the jarring action.

It is a further object of the invention to provide a jar of the character mentioned that is practical and dependable in operation and that is simple and inexpensive of manufacture. The tool provided by the present invention includes only three principal parts or sections.

Other objects and features of my invention will be best and more fully understood

from the following detailed description of a typical form and application of the invention, throughout which description reference will be had to the accompanying drawings, in which:

Fig. 1 is a longitudinal detailed sectional view of the tool, illustrating it in the contracted or unoperated position. Fig. 2 is a view similar to Fig. 1, showing the parts in the extended or jarring position. Figs. 3, 4, 5 are enlarged transverse detailed sectional views, taken as indicated by lines 3—3, 4—4, and 5—5 on Fig. 1 respectively. Fig. 6 is an enlarged transverse sectional view, taken as indicated by line 6—6 on Fig. 2. Fig. 1 shows the section C in a different rotative position than in Fig. 2, to illustrate the spiralled faces of the releasable holding means in cooperation. Sectional views, or Figs. 3 to 6, illustrate the body section A in 70 the rotative position shown in Fig. 2.

The jar or jarring tool provided by this invention includes, generally, a tubular body section A, two sections B and C extending into the opposite ends of the body section A, 75 and means 10 for releasably holding the sections B and C against relative longitudinal movement in a contracted position.

The body section A of the tool receives or houses the larger portions of the sections B 80 and C and loosely connects the sections B and C for limited relative longitudinal movement. The tubular section A is in the nature of a coupling member for loosely holding together the sections B and C. In accordance with the 85 invention, the body section A is an elongated tubular member having a central longitudinal opening 12. The body section A is preferably of uniform external diameter and may be of substantially the same diameter as the 90 drill pipe or the tool joints of the operating string in which the tool is connected. The lower end portion of the body opening 12 is of enlarged diameter to provide a downwardly facing annular shoulder 13 intermediate the ends of the section. A tubular nut 14 is provided on the lower end of the opening 12. The opening 16 in the tubular nut 14 is adapted to slidably and rotatably 95 pass the section C.

The section B which, in the particular case illustrated in the drawings, is the upper section of the tool extends into the upper end of the body section A. In the particular arrangement illustrated in the drawings, the section B is attached to the upper or main portion of the operating string. The upper end of the section B is shown screw-threaded into a socket 17 in a connecting member 18 of the operating string. The upper section B of the tool extends into the upper end of the body section A to project a considerable distance through the opening 12. An annular enlargement 19 is provided on the section B intermediate its ends to slidably fit the body opening 12. In the particular embodiment of the invention illustrated in the drawings, the body section A is connected to the upper section B to rotate therewith. Spaced longitudinal splines 20 are provided on the upper section B to slidably co-operate with keyways 21 in the walls of the upper portion of the opening 12. The body section A is the anvil element of the tool, while the upper section B is the hammer element; and the enlargement 19 of the section B is adapted to strike or co-operate with a shoulder 22 on the section A to effect the jarring action. In the form of the invention illustrated in the drawings, the shoulder 22 is an annular internal shoulder on the section A occurring at the lower ends of the keyways 21. Upon the release of the means 10, the upper section B moves upward relative to the body section A so that the upper end of the enlargement 19 is brought into hammering or jarring engagement with the annular shoulder 22. A central longitudinal fluid passage 27 is provided in the section B. The lower section C of the tool is intended to be connected with the object to be jarred, for example, it may be connected with a fishing tool engaging an object caught in the well. The lower end of the section C may be screw-threaded into a socket 23 in a connecting member 24 attached to the fishing tool or forming a part of the lower end of the operating string. The lower section C extends upwardly through the opening 16 in the nut 14 and has an upper or inner portion 25 of enlarged diameter rotatably carried in the opening 12 between the shoulder 13 and the upper end of the pin 15. The enlarged inner portion 25 of the section C is held between the shoulder 13 and the upper end of the pin 15 so that the section C is held against longitudinal movement relative to the section A. It is to be noted that the sections A and C are connected for free relative rotation or turning. A central longitudinal fluid passage 26 is provided in the section C.

The means 10 is provided to releasably connect the sections B and C against relative longitudinal movement in a contracted position and is operable to suddenly release the sections B and C for relative longitudinal

movement to permit the upper end of the enlargement 19 to strike the shoulder 22 to provide the jarring action between the sections. In accordance with the invention, the means 10 is adapted to be set or releasably locked by relative turning between the sections B and C and is adapted to be tripped or actuated by a heavy tensile strain transmitted through the tool. A socket or enlargement 28 is provided in the walls of the passage 26 within the enlarged part 25 of the section C. The socket 28 is annular or of round cross-sectional configuration and its lower wall 29 is in the nature of an annular sealing and bearing face and an abutment for co-operating with the lower end of the section B. The central portion of the bearing face and abutment 29 may be inclined downwardly and inwardly to the fluid passage 26. Diametrically opposite passageways 30 extend upwardly from the socket 28 to the upper end of the section C. The portions of the section C occurring between the passageways 30 are in the nature of longitudinal splines 31.

The upper section B extends downwardly through the upper end part of the passage 26 to project into the socket 29 when the parts are in the normal or contracted position, as illustrated in Fig. 1 of the drawings. The lower end of the section B is adapted to engage or co-operate with the abutment 29 at the lower end of the socket 28. The lower end of the section B is finished to have effective frictional and sealing engagement with the abutment 29 and its central portion may be inclined downwardly and inwardly to co-operate with the concave central portion of the abutment 29. When the sections B and C are in the contracted or unactuated position, the ends of the fluid passages 26 and 27 are in direct register and the lower end of the section B is adapted to co-operate with the abutment 29 to provide a seal between the sections B and C around the passages 26 and 27.

Spaced longitudinal splines 32 are provided on the lower end part of the section B. The splines 32 are proportioned to slidably pass through or co-operate with the passageways 30 when the sections A and B are operated between the contracted and extended positions. Inclined or helicoidal faces 33 are provided on the upper ends of the splines 32 to co-operate with correspondingly shaped faces 34 on the lower ends of the splines 31. In accordance with the invention, the helicoidal faces 36 and 37 are adapted to co-operate to bring the lower end of the section B into frictional and sealing engagement with the abutment 29 to releasably connect the sections against relative movement and to provide a seal between the sections upon the section B being turned relative to the section C. The pitch or inclination of the faces 33 and 34 is such that a heavy tensile strain

- put on the sections B and C causes the upper section B to be turned or partially rotated relative to the lower section C to disengage the inclined faces and release the sections 5 B and C for relative longitudinal movement so that the splines 32 may move upwardly through the passages 30 and the enlargement 19 is brought into hammering engagement with the shoulder 22. In practice, the faces 10 33 and 34 may be pitched in a right hand direction so that the sections B and C may be releasably connected against relative longitudinal movement by turning the section B in a clockwise direction relative to the section 15 C or by transmitting a right hand or clockwise torsional strain through the tool. When the faces 33 and 34 are pitched in the right hand direction, the operating or tensile strain for releasing the sections for the jar- 20 ring action causes the section B to be turned in a left hand or counter-clockwise direction. It has been found practical to pitch the faces 33 and 34 at approximately a 70° helix angle. The splines 31 and 32 are proportioned and 25 related so that the lower end of the section B is tightly wedged or forced against the abutment 29 to releasably hold the sections B and C against relative rotation and longitudinal movement. Upon a heavy tensile 30 strain being put on the tool by pulling upward on the operating string, the pitch or inclination of the faces 33 and 34 is such that the frictional engagement between the faces and the frictional engagement between the 35 lower end of the section B and the abutment 29 is overcome and the section B is partially rotated to bring the splines 32 into the passageways 30, permitting the section B to suddenly move upward and bring 40 the enlargement 19 into hammering engagement with the shoulder 22 of the section A. The splines 32 do not pass out of the passageways 30 when the section A is operated to the up or jarring position.
- 45 Vertical or longitudinal ribs 40 extend through the socket 28. The ribs 40 are provided to strengthen or reinforce the construction and are provided at diametrically opposite points. The strengthening ribs 40 occur 50 or extend downwardly from the upper wall of the socket 28 at the rear edges of the passageways 30. The helicoidal faces 34 join the forward edges of the ribs 40 and the ribs 40 are adapted to limit movement of the splines 32 55 onto the faces 34.
- In operation, the jar may be set for actuation by bringing the section A to a position where the splines 32 are within the socket 28 and then turning the section B in a direction 60 to cause the faces 33 and 34 to force the lower end of the section B against the abutment 29. The force or torsional strain employed to wedge or force the end of the section B against the abutment 29 governs or determines the 65 tensile strain necessary to release the sections
- and, accordingly, the force of the resultant jarring action. A heavy tensile or upward strain is put on the tool to cause the inclined or helicoidal faces 33 and 34 to release the sections B and C for relative turning and to 70 back the section B around to a position where the splines 32 may pass upwardly into the passageways 30. This upward movement of the section B brings the upper end of the enlargement 19 of the hammer section B into 75 jarring engagement with the anvil or body section A to impart the upward jarring action to the sections A and C and the parts connected therewith. It is to be noted that the splines 32 operate upwardly in and remain in 80 the passageways 30 during upward movement of the section B so that there is no relative rotative movement between the sections A and B. The splines 20 co-operate with the keyways 21 to connect the sections A and B for rotation so that the section A is turned with the section B relative to the section C upon actuation of the tool. When a heavy torsional strain is employed to force the lower 85 end of the section B against the abutment 29, 90 a very heavy tensile strain is required to release the faces 33 and 34 so that an extremely heavy upward blow or jar is obtained. It will be obvious that the strength or intensity 95 of the jarring action may be governed by the torsional force employed to releasably set the device in the contracted position.
- The jar may be actuated any desired number of times in rapid succession by maintaining a certain torsional strain on the tool and 100 operating string and reciprocating the string to actuate and re-set the tool. When a torsional strain is being maintained on the tool, the faces 33 and 34 are automatically brought into co-operation upon the drilling string being lowered to bring the splines 32 within the socket 28. The upward force or tensile strain required for tripping or releasing the sections B and C for relative longitudinal movement must be sufficient to overcome the frictional engagement between the lower end of the section B and the abutment 29 and between the faces 33 and 34 and also sufficiently heavy to cause the faces 33 and 34 to turn 110 the section B against the torsional strain on the tool. The tool does not, in any way, interfere with the free circulation of fluid through the operating string and an effective seal is provided between the sections B and C when the parts are in the contracted position.
- Having described only a typical, preferred form of my invention, I do not wish to limit myself to the specific details set forth, but 115 wish to reserve to myself any changes or variations that may appear to those skilled in the art or fall within the scope of the following claims:
- Having described my invention, I claim:
1. A well tool of the character described 120

including, two sections, means for releasably holding the sections against relative longitudinal movement, the said means being releasable upon a tensile strain being put on the sections and causing turning of one section relative to the other, and means for arresting longitudinal movement between the sections to effect a jarring action between them including a member rotatable relative to one section and slidably relative to the other section, a shoulder on said member, and a shoulder on one section adapted to strike the shoulder on the member.

2. A well tool of the character described including, two sections related for limited relative longitudinal movement, means for releasably holding the sections against relative longitudinal movement in a contracted position, said means including abutments on the sections, and helicoidal faces on the sections adapted to co-operate upon relative turning of the sections to bring the abutments into pressural frictional engagement, and means for arresting relative longitudinal movement between the sections upon release of the first mentioned means including a member rotatably connected with one section and slidably connected with the other section, a shoulder on the member, and a shoulder on said other section adapted to engage the shoulder on the member.

3. A well tool of the character described including, two sections related for limited relative longitudinal movement, means for releasably holding the sections against relative longitudinal movement in a contracted position, said means including abutments on the sections, and helicoidal faces on the sections adapted to co-operate upon relative turning of the sections to bring the abutments into pressural frictional engagement, and means for arresting relative longitudinal movement between the sections upon release of the first mentioned means including a tubular member surrounding the sections and rotatably connected with one section and slidably connected with the other section, a shoulder on the member, and a shoulder on said other section adapted to engage the shoulder on the member.

4. A well tool of the character described including, two sections related for limited relative longitudinal movement, means for releasably holding the sections against relative longitudinal movement in a contracted position, said means including abutments on the sections, and helicoidal faces on the sections adapted to co-operate upon relative turning of the sections to bring the abutments into pressural frictional engagement, there being fluid passages in the sections terminating at said abutments, the abutments being operable to form a fluid-tight seal around the passages when in engagement, and means for arresting relative longitudinal movement

between the sections upon release of the first-mentioned means including, a member rotatably connected with one section and slidably connected with the other section, a shoulder on the member, and a shoulder on said other section adapted to engage the shoulder on the member.

5. A well tool of the character described including, two sections related for relative longitudinal movement, splines on the sections adapted to slidably co-operate to hold the sections against relative rotation, means for releasably connecting the sections against relative longitudinal movement, said means being releasable upon a tensile strain being put on the sections, said means including abutments on the sections, and helicoidal faces on the splines of the sections adapted to co-operate upon relative turning between the sections to force the abutments into frictional engagement, and means for limiting relative longitudinal movement between the sections to cause an impact upon release of said means including a member rotatably connected with one section and slidably connected with the other section, a shoulder on the member, and a shoulder on the said other section adapted to engage the shoulder of the member.

6. A jarring tool including, a tubular section, a lower section having an enlargement rotatably fitting into the tubular section and held against longitudinal movement relative thereto, an upper section extending into and slidably relative to the tubular section, means for releasably holding the upper and lower sections against relative longitudinal movement, said means being releasable upon a tensile strain being put on the tool and including abutments on the upper and lower sections adapted to co-operate upon relative turning between the upper and lower sections to bring the abutments into frictional engagement, a shoulder on the tubular section and a shoulder on the upper section adapted to engage the first mentioned shoulder upon release of said means to cause an impact.

7. A jarring tool including, a tubular section, a lower section having an enlargement rotatably fitting into the tubular section and held against longitudinal movement relative thereto, an upper section extending into and slidably relative to the tubular section, means for releasably holding the upper and lower sections against relative longitudinal movement, said means being releasable upon a tensile strain being put on the tool and including abutments on the upper and lower sections, and inclined faces on the upper and lower sections adapted to co-operate upon relative turning between the upper and lower sections to bring the abutments into frictional engagement, fluid passages through the sections terminating at said abutments, the abutments being operable to form a fluid-

5 tight seal around the passages when in engagement, a shoulder on the tubular section and a shoulder on the upper section adapted to engage the first mentioned shoulder upon release of said means to cause an impact.

8. A well tool of the character described including, two sections related for limited relative longitudinal movement, means for releasably holding the sections against relative longitudinal movement in a contracted position, said means including abutments on the sections, and helicoidal faces on the sections adapted to co-operate upon relative turning of the sections to bring the abutments into pressural frictional engagement, and means for arresting relative longitudinal movement between the sections upon release of the first mentioned means including a member rotatably connected with one section and slidably connected with the other section, a shoulder on the member, and a shoulder on said other section adapted to engage the shoulder on the member, the pitch of said faces being such that the faces are adapted to co-operate to overcome the friction between the abutments and cause the release of the sections upon a predetermined tensile strain being put on the tool.

9. A well tool of the character described including, two sections related for limited relative longitudinal movement, means for releasably holding the sections against relative longitudinal movement in a contacted position, said means including abutments on the sections, and helicoidal faces on the sections adapted to co-operate upon relative turning of the sections to bring the abutments into pressural frictional engagement, and means for arresting relative longitudinal movement between the sections upon release of the first mentioned means including a member rotatably connected with one section and slidably connected with the other section, a shoulder on the member, and a shoulder on said other section adapted to engage the shoulder on the member, the pitch of said faces being such that they are adapted to co-operate to overcome the friction between the abutments to release the sections upon a tensile strain being put on the tool, and being such that the releasing tensile strain bears a given relationship to the torsional strain employed to set the abutments together.

10. A jarring tool including, a tubular section, a lower section having an enlargement rotatably fitting into the tubular section and held against longitudinal movement relative thereto, an upper section extending into and slidably relative to the tubular section, means for releasably holding the upper and lower sections against relative longitudinal movement, said means being releasable upon a tensile strain being put on the tool and including abutments on the upper and lower

sections, and inclined faces on the upper and lower sections adapted to co-operate upon relative turning between the upper and lower sections to bring the abutments into frictional engagement, an internal shoulder on the tubular section, and a shoulder on the upper section adapted to engage the first mentioned shoulder upon release of said means to cause an impact.

In witness that I claim the foregoing I have hereunto subscribed my name this 13th day of March 1931.

HARRY P. WICKERSHAM.
